CLAIM

The ornamental design for a smart watch, as shown and described.

DESCRIPTION

FIG. 1 is a first perspective view of a smart watch showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of an encircled portion of the smart watch labeled 9 in FIG. 1;

FIG. 10 is an enlarged view of an encircled portion of the smart watch labeled 10 in FIG. 1;

FIG. 11 is an enlarged view of an encircled portion of the smart watch labeled 11 in FIG. 2;

FIG. 12 is an enlarged view of an encircled portion of the smart watch labeled 12 in FIG. 2; and,

FIG. 13 is an enlarged view of an encircled portion of the smart watch labeled 13 in FIG. 2.

The evenly dashed broken lines shown in the drawings depict portions of the smart watch that form no part of the claimed design. The dot-dash broken lines encircling portions in FIGS. 1, 2, and 9-13 of the smart watch, illustrated in an enlargement in FIGS. 9-13 form no part of the claimed design.
